UNITED STATES PATENT OFFICE.

ANDREW J. BROOKINS, OF CHICAGO, ILLINOIS.

TRAIN-SIGNAL.

1,369,881.

Specification of Letters Patent.

Patented Mar. 1, 1921.

Application filed January 27, 1919. Serial No. 273,258.

To all whom it may concern:

Be it known that I, ANDREW J. BROOKINS, a citizen of the United States, and a resident of Chicago, in the county of Cook and 5 State of Illinois, have invented certain new and useful Improvements in Train-Signals for Use in the Cab of an Engine or Motor, of which the following is a full and complete description, sufficient to enable one 10 skilled in the art to understand, make, and use the same, when taken in connection with the drawing accompanying and forming a part hereof.

This invention relates to a device which 15 can be installed in a cab in position to be readily observed by a person or persons in the cab and which will indicate which one, if any, of a plurality of electric circuits is energized.

20 And the objects of the invention are to obtain a signal which is certain in its operation, when in operative condition, and which will automatically indicate its being in an inoperative condition; which is not liable to 25 get in inoperative condition; which consists of few parts joined to obtain a multiplicity of results; which is economically made; and which is durable.

Additional objects are disclosed by this 30 specification and the claims.

In the drawing referred to Figure 1 is an elevation, with the side of the case removed to disclose the operative parts of the construction to view; Fig. 2 is a sectional view 35 on line 2—2 of Fig. 1, viewed in the direction indicated by the arrows; and Fig. 3 is a diagram of the electric circuits forming elements in said construction.

A reference character applied to designate 40 a given part is used to indicate said part throughout the several figures of the drawing, wherever the same appears.

A represents the case of a device embodying this invention. B, B' indicate dials. A 45 portion of dial B is illustrated as broken away to expose to view the installation between said plates. b, b' indicate apertures in dials B, B'. C, C' indicate resistance coils. D represents a lever which is pivotally 50 mounted on shaft D', and D'' a spring arranged to yieldingly hold said lever with disks d, d', which are mounted on the ends of said lever, in front of apertures b, b'. E, E' illustrate electric lamps which may be 55 viewed through apertures b, b' when disks d, d' are in the position in which they are

illustrated in Fig. 1; and which are not exposed to view when said lever is turned, by spring D'', on said spring turning shaft D'', to bring said disks in front of said apertures; said disks forming shutters. F, F', F'', F''', f, f' and f'' indicate electric conductors. Resistance coils C, C', are in parallel with the respective lamps E, E'. G, G' represent electromagnets g, g' the 60 armatures thereof. H represents a commutator ring which is rigidly secured to armature and disk lever D, and h insulation on said ring. Armatures g, g', lever D and ring H are joined, to move in unison and 65 are moved by energization of magnets G, G', and by spring D'' when said magnets are not energized. I, I' and J, respectively represent brushes to commutator ring H. When lever D is in the position which is illustrated 70 in Fig. 1, the brushes I, I' are on insulation h; and when said lever is turned on its pivotal point, (by turning of shaft D') so that the disks d, d' are in front of apertures b, b', said brushes are in electrical contact 75 with commutator ring H and in electrical connection with brush J, which is, at all times, in electrical contact with said ring. Conductor f is electrically attached to brush I; conductor f' to brush I', and conductor 80 F'' to brush J. D'' represents a spring which is arranged to yieldingly hold lever D in position with disks d, d' in front of apertures b, b'; and when said lever is in the last named position the brushes I, I' not being 85 on insulation h the circuits of which said brushes and brush J are elements are continuous. As stated, when the coils of electromagnets G, G', are not energized spring D'' controls the position of lever D, and 90 when said coils are energized said magnets control said position, (by attracting armatures g, g'), moving said lever from the position in which it is yieldingly held by spring D'' into the position in which it is 95 illustrated in Fig. 1, against the tension of said spring.

K, K', and K'' indicate terminals, (see Fig. 3), and L a movable conductor the free end of which is adapted to be moved into 105 electrical contact with any one of said terminals. M, (Fig. 3) indicates a vertically movable plunger. When plunger M is in its lowest position the movable conductor L is in electrical contact with terminal K'', 110 and from said terminal movable circuit closer l is successively brought into electrical

contact with terminals K' and K, as said plunger is raised to its highest position. The means to move and retain plunger M in a determined position and thereby control 5 the position of movable conductor L forms no part of this invention, and it may be considered, so far as this invention and its operation is concerned, that the position of said movable conductor L relative to terminals K, K', and K'' controls the several operations and functions of the apparatus embodying this invention whether said movable conductor be moved manually, mechanically, or otherwise, and hence said movable 10 conductor is merely diagrammatically indicated in Fig. 3.

As the normal condition of a track on which a train or other moving body is traveling, on the cab of which this apparatus is 15 installed, is "clear", what I call the normal position of movable conductor L is with the free or movable end thereof in electrical contact with terminal K (with lamp E energized), and it is so illustrated, and indicated. When said track is not "clear"; but is under such conditions that caution should 20 be exercised by the engineer or other person in control of said train, the "caution" signal is given or displayed; said caution signal 25 being the lighting of lamp E', and in such case the free or movable end of said movable conductor L is in electrical contact with terminal K'; and when the condition of 30 said track is such that there is danger to said train proceeding, said free end is in contact with terminal K'', neither lamp E or E' is 35 lighted, and both said lamps are obstructed by disks d, d' being in front of apertures b, b', where they are yieldingly held by spring D''. 40 N, (Fig. 3,) indicates a battery or other suitable means to energize the several circuits which are illustrated and hereinafter traced; and n represents a conductor from 45 said energizing means to the pivoted end of movable conductor L.

Said circuits are traced as follows:—

Assuming movable lever D to be in the position in which the disks d, d', are in front of apertures b, b', the danger signal having 50 been previously maintained and a change in the position of movable conductor L having occurred, there will be a closed circuit from energizing means N which includes conductor n, movable conductor L, 55 (said conductor being on terminal K, as illustrated), conductors F, f, brush I, (it not being on insulation h), commutator ring H, brush J and conductor f'' to conductor F'', and thence through the coils 60 of magnets G, G', and on conductors F''' back to N. This circuit shunts the signal E and resistance C, and said signal will not be well displayed until the lever D has been turned on its pivot, by the attraction 65 of armatures g, g' by magnets G, G', to re-

move the disks d, d' from in front of apertures b, b'; that is, to the position in which it is illustrated in Fig. 1. Said turning brings brushes I, I', on to insulation h of the commutator ring H, and the last above recited 70 circuit, of which said ring and said brushes are elements, is broken, and the signal E will then be well displayed.

Assuming movable conductor L to be in electrical contact with terminal K', a closed 75 circuit will be formed comprising the following members,—from generating means N, on conductor n, movable conductor L, conductor F', lamp E' and resistance C', conductor F'', the coils of magnets G, G', 80 conductors F''' to N, when lever D is in the position in which it is illustrated in Fig. 1.

Assuming lever D to be in position with disks d, d' covering apertures b, b', at the time of the establishing of the last above 85 named circuit, there will also be an additional circuit established, which may be traced as leading from conductor F' on to conductor f', brush I', ring H, brush J, to the coils of magnets G, G'. This circuit includes also the energizer N, conductor n, movable conductor L, conductor F', and conductors F''' which are common to it and to the last preceding circuit; and the lamps E' and resistance C' are shunted thereby. 90

It will be observed that the coils of magnets G, G' and conductors F''' are common to all of the circuits.

The operation of the apparatus is,—When a circuit breaker comprising movable conductor L and terminal K, (or K'), is closed, a circuit of which said circuit breaker and lamp E (or E'), and the corresponding resistance (C or C') are elements is closed and energized and the one of said lamps 100 which is in said circuit is lighted. When said circuit breaker is open both circuits of which movable conductor L of said circuit breaker is an element are open, and "dead," and lever D is moved by spring D'' to a position where disks d, d' are in front of apertures b, b', (magnets G, G' not being energized). Said circuits being dead if it be assumed that movable conductor L is moved to again bring it in electrical contact with the terminal K, (as indicated in Fig. 3), the circuit which is traced from N, on n, L, K, F, f, I, H, J, coils of magnets G, G', and F''' to N, is again established; as is also the circuit which includes lamp E and resistance C; and the lever D will be moved to expose to view said lamp; and the lamp will be lighted. 115

Attention is directed to the fact that by the installation of this apparatus in the cab 125 of an engine or motor, it will indicate the condition of the track ahead, as follows; by lighting and exposing to view lamp E if the "clear" signal corresponds with said condition; the lamp E' if the "caution" signal 130

corresponds; and the lever D with disks d, d' covering apertures b, b', if the "danger" signal corresponds; and if the device be rendered inoperative, as by failure of energizing means N to properly function, the "danger" signal will be given.

I claim:

1. In a train signal, electric lamps, electromagnets and conductors in electric connection with said lamps and with the coils of said magnets to form a plurality of electric circuits, armatures to said magnets, a movable circuit closer arranged to break said circuits and in selective order to close said circuits, and means common to said circuits to energize the closed one thereof, means to obstruct a view of said lamps, and means comprising said magnets and armatures to remove said obstruction.
2. In a train signal, electric lamps, resistance coils, electromagnets, and conductors in electric connection with said lamps and with the coils of said magnets to form a plurality of electric circuits in which said lamps and resistance coils are in multiple and said magnets are in multiple, armatures to said magnets, a movable circuit closer arranged to break said circuits and in selective order to close said circuits, and means, common to said circuits to energize the closed one thereof, means to obstruct a view of said lamps, and means comprising said magnets and armatures to remove said obstruction.
3. In a train signal, the combination of, an electric signal, yielding means to obstruct the view of said signal and means to remove and maintain said obstruction removed, said

means to remove and maintain comprising electromagnets and the armatures thereof, 40 an electric circuit comprising conductors and a circuit breaker controlled by said means to remove and maintain, and a second electric circuit comprising conductors and said signal, said circuits also comprising, 45 as common thereto, said magnets, a movable circuit closer and means to energize said circuits.

4. In a train signal, electric lamps, means to obstruct a view of said lamps, means to 50 yieldingly hold said means to obstruct in obstructing position, electromagnets and armatures thereto arranged to control the position of said means to obstruct, electrical conductors electrically connected to said 55 lamps and to the coils of said magnets and adapted to form elements of electric circuits, in combination with additional conductors, a circuit breaker arranged to make said additional conductors continuous and 60 to break the continuity thereof, on said means to obstruct being in obstructing position and moved therefrom, said additional conductors and circuit breaker adapted to form elements of additional circuits of 65 which said coils are also elements, and said last named circuits arranged to shunt said lamps, additional means to control the continuity of the conductors in said circuits, and means to energize closed ones of said 70 circuits.

ANDREW J. BROOKINS.
